GEORGE ROTTMAN

By his Attorney

William F. Hinkel

UNITED STATES PATENT OFFICE.

GEORGE ROTTMAN, OF NEW YORK, N. Y.

ARMBAND.

1,410,222.

Specification of Letters Patent. Patented Mar. 21, 1922.

Application filed January 12, 1920. Serial No. 350,943.

To all whom it may concern:

Be it known that I, GEORGE ROTTMAN, a citizen of the United States, residing in New York, in the county of New York and State of New York, have invented certain new and useful Improvements in Armbands, of which the following is a specification.

My invention relates to an improvement in arm bands for engaging the sleeve of a garment and holding said sleeve in the required position.

An object of my invention is to provide an arm band which can be adjusted according to the size of the wearer's arm; which will be simple in construction and capable of being easily and cheaply manufactured; and which will be of such design as to present a neat and even ornamental appearance when finished.

This object and other objects and advantages of my invention will appear fully from the following specification, including the accompanying drawings; the novel features of my invention being precisely defined in the appended claims; and while the drawings show the best form of my invention now known to me, I reserve the right to make changes in what is actually disclosed herein, without departing from the scope and spirit of my invention, as indicated by the broad meanings of the terms in which the claims are expressed.

On the drawings:—

Figure 1 is a front view of an arm band according to my invention;

Figure 2 is a top view of part of same;

Figure 3 is an inside view, presenting the link by which the ends of the band are connected;

Figure 4 is a view of this link detached; and

Figure 5 shows a blank which can be bent into shape and used in place of this link, if desired.

The same numerals identify the same parts throughout.

As shown in the drawings, the band comprises a strip of elastic or non-elastic cloth 1, having its ends connected by a link 2.

Figure 1 shows the band as viewed from the front, with the ends joined; and Figures 2 and 3 illustrate the band in part only; but one will understand that the band makes a complete loop to encircle the arm on which it is placed. One end of this band is fixed to one end of the link and the other end

of the band is passed through the opposite extremity of the link and secured to the body of the strip by means of a suitable clasp 3, this clasp permitting the end to which it is attached to be drawn through the adjacent extremity of the link to a greater or less extent and thus make the arm band larger or smaller, as desired. To the link is secured a bow 4, the middle of which is attached to the middle of the link and the ends of which are wide enough to hide the extremities of the link and thus conceal the ends of the band; with the result that the entire articles can have an attractive appearance.

The clasp 3 may be an ordinary clasp, such as is used on suspenders and similar devices; and may comprise a plate 5 to which the end of the band that is passed through one extremity of the link 2 is made fast. This plate 5 has over-turned perforated ends 6 providing bearings for a clip 7 having trunnions 8 to engage the said bearings, so that the clip can be opened and closed. This clip has its inner end bent at a right angle, as indicated in Figure 2, and when the clip is turned down against the band, the inner end is forced against the band and slipping is prevented. As this clasp is well known, further description of same is not necessary.

The link 2 may have the form of an open frame made by bending wire, for instance, into proper shape. The ends 9 are expanded while the middle is narrow, providing a shank 10 joining the ends together; these ends forming, in effect, loops 11 for engaging the ends of the band 1. When the strip 1 is secured to these loops, the ends of the band are effectively connected and the band can be adjusted at will. To join the band to the link, one end of the band is passed through one loop 11, and sewed, or held by a clip 12, as shown in Figures 2 and 3, or 100 in any other suitable way, and the other end of the band may be passed between the plate 5 and clip 7, and through the other loop 11, and then through a slot 13 in the plate 5, where it is engaged by a similar 105 clip 12.

The bow 4 is secured to the link 2 by means of a clamp or fastening element 14 bent around the shank 9; gripping the bow and holding it in place with its ends overlying and concealing the wide ends 9 of the link providing the loops 11.

Hence, when the band is applied to the arm, the link 2 is entirely hidden from view; the ends of the band being secured as effectively if the ends were directly and securely attached to each other; while at the same time, the band can be made larger or smaller by manipulating the clasp 3, and sliding it towards or from the link 2.

In Figure 5, I show a link in the form of a stamping 15 which comprises widened ends 16 having slots 17 and connected by a shank 18. From the lateral edges of this shank extend opposite projections 19. To use this blank, the ends of the band are passed through the slots 17 in the same fashion as above described, in connection with the widened ends 9 of the link 2; and to secure the bow to this blank, the projections 19 are simply turned over and bent down to clamp the middle of the bow against the shank 18 of the blank, the wide ends of the bow then hiding the ends 16 and the slots 17 as in the former case.

The band is thus exceedingly simple and can be adjusted as desired, and is neat and attractive to the eye. The result is the same where a link consisting of the bent wire or some other substance is employed, or the link shown in Figure 5, made of stamped metal or other material.

Having described my invention, what I believe to be new and desire to secure and protect by Letters Patent of the United States is:—

1. An arm band comprising a strip, a link connecting the ends of said strip, said link

having widened ends and a relatively narrow shank between the same, and a bow secured to the shank of said link and having widened ends to hide the ends of said link. 40

2. An arm band comprising a strip, a link, the strip having one end affixed to said link and the other end adjustably engaging the link, said link having a narrow middle portion, and a bow secured to the middle 45 portion and having its ends concealing the link and the ends of said strip.

3. An arm band comprising a link of bent material, having widened ends providing loops and a connecting portion between said 50 ends constituting a relatively narrow shank, a strip having one end fixed to one end of the link and having its opposite end adjustably engaging the other end of the link, a bow having its ends covering the widened 55 ends of said link and a fastening element encircling the shank of the link and the middle of the bow and securing them together.

4. An arm band comprising a link having 60 widened ends and a relatively narrow portion connecting said ends, said ends having transverse slots, a strip having one end secured to one end of the link in the slot therein and having its opposite end passed 65 adjustably through the opposite slot, and a bow secured to said link and serving to conceal same.

In testimony whereof, I have signed my name to this specification this 2nd day of 70 December, 1919.

GEORGE ROTTMAN.
